CUFF LINK OR THE LIKE

Frederick W. Moulson, Rehoboth, Mass., assignor to B. A. Ballou & Co. Incorporated, a corporation of Rhode Island

Application March 17, 1950, Serial No. 8,592

Term of patent 14 years

(Cl. D17—7)

To all whom it may concern:

Be it known, that I, Frederick W. Moulson, a citizen of the United States of America, residing at Rehoboth, county of Bristol, State of Massachusetts, have invented a new, original, and ornamental Design for a Cuff Link or the like, of which the following is a specification, reference being had to the accompanying drawing, forming a part thereof:

Fig. 1 is a top plan view of a cuff link or the like, showing my new design; and

Fig. 2 is a side elevation thereof.

The dominant part of the design is shown in full lines.

I claim:

The ornamental design for a cuff link or the like, substantially as shown and described.

FREDERICK W. MOULSON.
